DESIGN FOR A LETTER OPENER

Garfield L. Beckstrom, Chicago, Ill., assignor to Autopoint Company, Chicago, Ill., a corporation of Illinois

Application January 10, 1948, Serial No. 143,651

Term of patent 14 years

(Cl. D74—1)

To all whom it may concern:

Be it known that I, Garfield L. Beckstrom, a citizen of the United States, residing at Chicago, in the county of Cook and State of Illinois, have invented a new, original, and ornamental Design for a Letter Opener, of which the following is a specification, reference being had to the accompanying drawing, forming a part thereof.

In the drawing:

Fig. 2 is an edge elevational view thereof;

Fig. 3 is a bottom plan view of Fig. 1; and

Fig. 4 is a top plan view thereof.

I claim:

The ornamental design for a letter opener, substantially as shown.

GARFIELD L. BECKSTROM.
